UNITED STATES PATENT OFFICE.

FRANZ GUILLEAUME, OF BONN, GERMANY.

DESIGN FOR A PLATE OR SIMILAR ARTICLE.

SPECIFICATION forming part of Design No. 21,476, dated April 19, 1892.

Application filed March 15, 1892. Serial No. 425,039. Term of patent 3½ years.

To all whom it may concern:

Be it known that I, FRANZ GUILLEAUME, a subject of the Emperor of Germany, residing at Bonn, in the Province of Rhenish Prussia, Germany, have invented certain new and useful Improvements in Designs for Dishes and China-Ware; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The distinguishing characteristics of my design are shown in the accompanying drawings, Figure 1 being a plan and Fig. 2 a sectional view, in which—

The reference-letter *a* represents a plate substantially circular in general outline, although the edge thereof is uneven in conformity with the decorations.

On one side of the plate there is a scroll *b*, which is a continuation of a leaf *c*. Adjacent to the upper outer edge of the leaf is a curved object *d*, which forms a portion of the edge of the plate. On the upper end of this curved object is located a shell-like piece *e*, on which is formed a series of spots *f*, and the whole of the portion *e* is shaded to appear somewhat like the edge of a shell, and on the right thereof it continues and terminates in a tapering piece *g*. Intermediate lateral dashes *h* are located where the part *e* leaves off and the part *g* commences. On the inner edge of the part *e* is formed a scroll *i*, the lower end of which is provided with a rosette *j*. Below the lower edge of this rosette is formed curved pieces *k* and *l*, which extend

from the rosette nearly to the edge of the plate, where the lower end of the piece *c* becomes entwined with a feather-like piece *m*. Diametrically opposite the portion of the plate occupied by the foregoing figures the edge of the plate is fluted to imitate two edges 45 *n* and *o*, resembling a shell. These edges overlap and are irregular. The under fluted edge *n* is provided with depressions *p*. Extending from the lower side of this double-edged design is a curved bar *q*, which forms 50 the edge of the plate. The end of the bar *q* terminates in an inward and backward scroll *r*. Continuing along the edge of the plate extends a feather-like scroll *s*, provided with an inward portion *t*, and adjoining the part *s* is 55 a fluted shell-like piece *u*, curved inwardly and provided with depressions *v*. The edge of the plate is made undulating at this point. Diametrically opposite this fluted portion *u* is formed another fluted part *w*, which curves 60 upwardly like a shell, and obliquely below it are formed inwardly-projecting scrolls *x*, to the sides of which extends a tapering part *y*, which joins the double-edged design *n*. All of the figures of parts just described are formed in 65 relief around the flange *z* of the plate. In cross-section the flange *z* of the plate constitutes a reverse curve, as seen in Fig. 2.

What I claim is—

The design for a plate or similar article, 70 substantially as herein shown and described.

In testimony whereof I affix my signature in presence of two witnesses.

FRANZ GUILLEAUME.

Witnesses:

P. NOTHBORN,
KARL SCHWARZ.
